MOTOR ACTUATED FURNACE CONTROL

Filed June 17, 1929 2 Sheets-Sheet 2

UNITED STATES PATENT OFFICE

ALBERT PENN, OF DES MOINES, IOWA, ASSIGNOR TO PENN ELECTRIC SWITCH CO., OF DES MOINES, IOWA, A CORPORATION OF IOWA

MOTOR ACTUATED FURNACE CONTROL

Application filed June 17, 1929. Serial No. 371,537.

The object of my invention is to provide a motor actuated furnace control of simple, durable and comparatively inexpensive construction.

More particularly it is my object to provide a furnace control in which a motor is continuously operated while it is desired to augment the fire in the furnace by opening the draft door and closing the check door, the motor being operatively connected with these doors in such a way that it intermittently causes opening of first one and then the other.

Still another object is to provide a motor actuated furnace control having a crank arm operatively connected with the draft and check doors of a furnace whereby the crank when in one position will open the draft door and when in another position will open the check door, means of adjustment being provided to regulate the amount of opening of each door as desired.

Still another object is to provide thermostatic means within the room heated by the furnace for controlling the draft doors depending upon the temperature of the room.

Still a further object is to provide in connection with my control mechanism, means for insuring that when the thermostat is in non-controlling or off position the furnace control will automatically continue to be actuated to a predetermined point.

Still a further object is to provide a clutch mechanism actuated as the result of a thermostatic element for causing the furnace control to be actuated from a continuously operated motor.

Another object is to provide a night control for preventing operation of the furnace control during the night, such night control being associated with the furnace control in such a way that the furnace control will again become operative at a predetermined hour in the morning.

Another object is to provide a modified form of construction in which the room thermostat controls the motor for causing it to operate only when the thermostat is in controlling position and calling for augmentation of the furnace fire.

With these and other objects in view my

invention consists in the construction, arrangement and combination of the various parts of my device, whereby the objects contemplated are attained, as hereinafter more fully set forth, pointed out in my claims, and illustrated in the accompanying drawings, in which:

Figure 1 is a side elevation of a furnace showing my improved type of motor actuated control installed therewith.

Figure 2 is an enlarged view of the opposite end of the furnace control showing the cover thereof removed.

Figure 3 is an electrical diagrammatical view of the wiring for the furnace control.

Figure 4 is a sectional view on the line 4—4 of Figure 2.

Figure 5 is an end elevation of a portion of the device as viewed in the direction of the arrow 5, adjacent Figure 4.

Figure 6 is a semi-diagrammatic view of a modified form of control in which a weight is used associated with the draft and check doors of the furnace; and

Figure 7 is an electrical diagrammatic view of a modified form of construction.

On the accompanying drawings, I have used the reference numeral 10 to indicate generally a furnace. The draft door of the furnace is indicated at 12. The check door thereof is indicated at 14. A basement ceiling is indicated at 16, and a chimney at 18.

My improved type of motor actuated furnace control consists of a casing 20 provided with a removable cover 22. Within the casing 20, I mount an electric clock 24. In place of the clock 24, any suitable type of electric motor may be provided. Projecting from the clock or motor 24 is a shaft 26 having thereon a pinion 28.

Journaled in bearings 30 extending inwardly from one side of the casing 20 is a shaft 32 to which is secured a gear 34. Pivotally mounted on the shaft 32 is a pair of arms 36 carrying a shaft 38. Rotatably mounted on the shaft 38 is a pinion 40 meshing with the gear 34.

Within the casing 20 is provided a solenoid 42 having therein a plunger 44. The plunger 44 has an extension 46 pivotally connected

90

95

100

with a pin 48 mounted in the upper ends of the arms 36. A spring 50 is provided for constraining the plunger 44 and the arms 36 toward movement in one direction. Such movement is limited by stop fingers 52 formed on the arms 36. The stop fingers 52 normally engage the inner surfaces of the casing 20, due to the action of the spring 50.

From the description of the parts just described it will be obvious that energization of the solenoid 42 will draw the plunger 44 inwardly, thereby causing the pinion 40 to mesh with the pinion 28 as shown in dotted lines in Figure 2. Rotation of the pinion 28 will thus be transmitted to the gear 34 and then to the shaft 32.

On the outside of the cover 22, a crank arm 54 is connected with the shaft 32 as clearly shown in Figures 4 and 5 of the drawings. The crank arm 54 is provided with a slot 56 through which a pivot bolt 58 extends. A sleeve 60 and a washer 62 are mounted on the bolt 58 and securely clamped thereon against the crank arm 54 by a wing nut 64. Journaled on the sleeve 60 between the washer 62 and the crank arm 54 is a connecting fitting 66. A draft chain 68 and a check chain 70 are connected with the opposite ends of the fitting 66 and extend to the draft door 12 and the check door 14 respectively. Brackets 72 carrying pulleys 74 may be provided for transmitting the movement of the chains 68 and 70 to the doors 12 and 14.

Secured to the shaft 32 within the casing 20 is a switch actuating arm 76. The arm 76 is adapted to coact with a switch blade 78 at one position of the rotation of the shaft 32 as shown in Figure 2, for the purpose of separating a contact 80 thereon from a stationary contact 82. The stationary contact 82 is supported on a post 84 secured to the casing 20 and the switch blade 78 is secured to a post 86. The posts 84 and 86 are preferably of insulating material.

In connection with my motor actuated furnace control I have provided a night control which is operative to render the furnace control inoperative during the night after banking the fire. Such night control may consist of a switch structure comprising a stationary switch arm 100 and a movable switch arm 102 (see Figure 2). A spring actuated catch 104 is adapted to coact with the movable switch arm 102 to keep the switch arms separated during the night.

A push button 106 of insulation is provided for causing the latch 104 to coact with the switch arm 102. The button 106 is adapted to be pushed inwardly either just before or just after the fire in the furnace 10 is banked for the night.

It will be noted that one end of the latch 104 extends through a slot 108 in the casing of the motor 24. Within the casing of the motor a cam arm 110 is mounted and is ad-

justably secured to a disk 112 by means of a thumb screw 114. The disk 112 is so geared to the motor mechanism of the clock that it rotates once every 24 hours, and the cam arm 110 is adjustable for setting it at the desired hour in the morning for the furnace control to begin operating.

Practical operation

Referring to Figure 3 I have shown a wiring diagram for my improved furnace control. A room thermostat is indicated at A and includes an expansible member 88 acting upon a switch arm 90 for separating it from a switch contact 92 upon expansion of the member 88 to a predetermined position. Assuming that the parts are in the position shown in Figure 1 and the room in which the thermostat A is connected becomes cold, the member 88 will contract for allowing the arm 90 to engage the contact 92 as shown in Figure 3, whereupon an electric circuit will be established from a supply wire 94 through a wire 96 to the solenoid 42, and back to a supply wire 98. Assuming that the crank arm 54 is originally in the position shown in Figure 1, energization of the solenoid 42 will cause the rotation of the shaft 32 for pulling the chain 68 and thereby opening the draft door 12 and closing the check door 14 during one half of a revolution of the crank arm 36. During the other half of such revolution, the door 12 will be closed and the door 14 opened, and as the revolutions continue, this intermittent opening and closing of the doors will continue also.

In the operation of the night control shown in Figure 2, the push button 106 is manipulated when the fire is banked at night and separates the contact 102 from the contact 100 thereby breaking the circuit to the clutch solenoid 42 and thermostat A as shown in Figure 3.

Then in the morning (at six o'clock as shown in Figure 2) the cam arm 110 will engage the latch 104 for releasing the switch arm 102 whereupon the circuit will be reestablished for opening the furnace door 12 and closing the door 14 due to the fact that the thermostat A will be in closed position. Thereafter the furnace control will be actuated automatically for raising and maintaining the temperature of the room as desired.

This causes the fire in the furnace to be augmented for sending a "shot" of heat up to the room, after which the furnace is shut off for allowing the heat in the furnace jacket to continue its upward rise to the room. This intermittent operation prevents overheating of the room caused by opening the draft 12 and leaving it open until the room thermostat actuates the device to again close it.

When the room thermostat A does become warm enough to separate the arm 90 from

the contact 92, the solenoid 42 will continue to be energized by the switch contacts 80 and 82. This prevents stopping of the shaft 32 until the arm 76 engages the switch arm 78 for separating the contacts 80 and 82, whereby the crank arm 54 will stop in the desired position for leaving the draft door 12 closed and the check door 14 open.

In Figure 6 I have illustrated a construction in which the switch contacts 80 and 82 may be dispensed with. This construction includes a weight 100 which acts to rotate the crank arm 54 to the position shown whereafter the clutch plunger 44 is released by de-energization of the solenoid 42. It will be obvious that no matter what position the arm 56 may stop in, the weight 100 will automatically cause closing of the draft door 12 and opening of the check door 14.

In Figure 7 I have illustrated a modified form of construction in which the thermostat A controls the motor 24 directly, so that the motor is operated only when the thermostat is in controlling position. In connection with this type of installation the automatic stop switch 78 would be provided for insuring the stopping of the motor at certain proper positions for closing the draft 12 and opening the check 14.

The shaft 32 may be rotated at a predetermined speed, one revolution per five minutes, for example, and the member 66 may be adjusted relative to the crank arm 54 whereby the doors 12 and 14 would be opened one-fifth of a revolution each five minutes, or may be opened for a longer period by adjusting the bolt 58 farther from the shaft 32. This adjustment can be made to cause proper operation of the furnace depending on changes in weather conditions and changes in fuel.

Some changes may be made in the construction and arrangement of the parts of my device without departing from the real spirit and purpose of my invention, and it is my intention to cover by my claims, any modified form of structure or use of mechanical equivalents, which may be reasonably included within their scope.

I claim as my invention:

1. In a motor actuated furnace control, a motor, means for connecting said motor with a furnace controlling device and for cyclically operating said device by said motor through different positions of the device, means for rendering said furnace controlling device inoperative a predetermined length of time, said means being cooperatively associated with the motor and actuated thereby to render the furnace control again operative at a predetermined time.

2. In a motor actuated furnace control, a motor, means for connecting said motor with a furnace controlling device and for cyclically operating said device by said mo-

tor through different positions of the device, said means being actuated by a room thermostat, means to insure the stopping of the device in a predetermined position after the thermostat reaches a predetermined point in its range of operation, means for rendering said furnace controlling device inoperative a predetermined length of time, said means being cooperatively associated with the motor and actuated thereby to render the furnace control again operative at a predetermined time.

3. In a motor actuated furnace control, a motor, means for supplying current thereto, furnace controlling mechanism and temperature responsive means to control the operation thereof, said furnace controlling mechanism being operatively connected with said motor and repeatedly operated through a cycle of positions while said temperature responsive means is in one of its positions.

4. In a motor actuated furnace control, a motor, means for supplying current thereto, furnace controlling mechanism operatively connected therewith and cyclically operated through different positions thereby and a room thermostat responsive to the temperature in a room heated by a furnace controlled by said furnace controlling mechanism and operable for rendering said furnace controlling mechanism operable when the temperature of said room is low and inoperative when said temperature is high.

5. In a motor actuated furnace control, a motor, means for supplying current thereto, furnace controlling mechanism operatively connected therewith and cyclically operated through different positions thereby and a room thermostat responsive to the temperature in a room heated by a furnace controlled by said furnace controlling mechanism and operable for rendering said furnace controlling mechanism operable when the temperature of said room is low and inoperative when said temperature is high and means to insure stopping of said furnace controlling mechanism in a predetermined position after said room thermostat has become effective to render said furnace controlling mechanism inoperative.

6. In a motor actuated furnace control, an electrically operated motor, furnace controlling mechanism operatively connected therewith and cyclically operated through different positions thereby, a control circuit for rendering said furnace controlling mechanism operative and inoperative and thermostatic means for energizing and de-energizing said control circuit.

7. In a motor actuated furnace control, a motor, a crank operatively connected therewith, means for operatively connecting said crank with a controlling device of a furnace, said first mentioned operative connection comprising mechanism operatively engage-

able with the shaft of said motor, thermostatic means for causing such engagement of said mechanism and disengagement thereof and weight means for insuring that said control device will stop in a predetermined position after such disengagement.

8. In a motor actuated furnace control, a circuit, a motor connected thereacross, a crank operatively connected with said motor, means for operatively connecting said crank with a controlling device of a furnace, said first mentioned operative connection comprising mechanism operatively engageable with the shaft of said motor, thermostatic switch means for causing such engagement of said mechanism and disengagement thereof and circuit breaking means for insuring that said control device will stop in a predetermined position after such disengagement.
10. In a motor actuated furnace control, a circuit, a motor connected thereacross, a crank operatively connected therewith, means for operatively connecting said crank with a controlling device of a furnace, said first mentioned operative connection comprising mechanism operatively engageable with the shaft of said motor, thermostatic switch means for causing such engagement of said mechanism and disengagement thereof and
- 15 means for insuring that said control device will stop in a predetermined position after such disengagement.
20. In a motor actuated furnace control, a circuit, a motor connected thereacross, a crank operatively connected therewith, means for operatively connecting said crank with a controlling device of a furnace, said first mentioned operative connection comprising mechanism operatively engageable with the shaft of said motor, thermostatic switch means for causing such engagement of said mechanism and disengagement thereof and
- 25 means for insuring that said control device will stop in a predetermined position after such disengagement, said means comprising a switch actuated by said motor and with said crank.
30. 10. In a motor actuated furnace control, a continuously operating motor, means for connecting said motor with a furnace controlling device and for cyclically operating said device by said motor through different positions of the device, means for rendering said furnace controlling device inoperative a predetermined length of time and means operated by the motor to restore the furnace controlling device to operative position.
